UNITED STATES PATENT OFFICE.

ALEXANDER X. KENNEDY, OF TYRONE, PENNSYLVANIA, ASSIGNOR OF
ONE-HALF TO THOMAS F. McLAUGHLIN, OF SNOWSHOE, PENNSYLVANIA.

SAFETY-BRAKE PAWL.

No. 802,866.

Specification of Letters Patent.

Patented Oct. 24, 1905.

Application filed January 16, 1905. Serial No. 241,319.

To all whom it may concern:

Be it known that I, ALEXANDER X. KENNEDY, a citizen of the United States, residing at Tyrone, in the county of Blair and State of Pennsylvania, have invented new and useful Improvements in Safety-Brake Pawls, of which the following is a specification.

This invention relates to a safety-brake pawl for use in connection with ratchet-wheels of brake-shafts to secure said shafts against retrograde rotation when the brakes are applied, the object of the invention being to provide a pawl appliance which is simple and inexpensive of construction, capable of being used in place of the ordinary brake-pawl and in connection with the usual type of ratchet-wheel, which may be conveniently retracted when positively operated to release the brake-shaft, but cannot become displaced by ordinary shocks or jars, and which will be effectually protected from snow and ice and prevented from becoming inoperative thereby or affected by other climatic changes or conditions.

With this and other objects in view the invention consists of the features of construction, combination, and arrangement of parts hereinafter fully described, reference being had to the accompanying drawings, in which—

Figure 1 is a top plan view of a brake-pawl embodying my invention, showing the same in engagement with the ordinary type of ratchet-wheel. Fig. 2 is a side elevation of the same, and Fig. 3 is a horizontal section through the pawl and its supporting block or casting and the end wall of the cover-plate coöperating with said block or casting to form the pawl-casing.

Referring now more particularly to the drawings, the numeral 1 represents a suitable support, which may be a portion of the wall or platform of a car or a bracket connected thereto and through which extends the brake-shaft 2, to which is fixed the usual ratchet-wheel 3.

The pawl mechanism comprises a block or casting 4, provided at one end with a right-angularly-extending arm 5, which is bifurcated at its free end to form a receiving-slot 6, the inner wall of the block or casting 4 being extended from the other end of said block on a gradual curve, as indicated at 7, to thicken or strengthen the block at its point of junction with the arm 5. The upper sur-

face of the arm 5 projects above the upper face of the block 4 and is provided with a plane-surfaced inner edge forming an abutting shoulder 8. The block 4 is designed to rest with its lower surface against the support 1 and is of sufficient depth or thickness to provide for the formation of the slot 6 of sufficient depth to receive a pawl of requisite width and thickness and to form with a cover-plate 8^a a casing to protect the body portion of the pawl and its actuating-spring. The plate 8^a is approximately rectangular in form and rests against the upper surface of the block or casting 1 and against the shoulder 8 and is provided at its end opposite said shoulder 8 with a downwardly-projecting flange 9, which extends downward into contact with the support 1, the block 4, with its arm 5, thus forming the rear wall and one of the side walls, the plate 8^a the top wall, and the flange 9 the other side wall of a casing which is open at its forward end or at the end opposite the said block 4.

The pawl 10 is properly curved to engage the teeth of the ratchet-wheel 13 and is provided with an enlarged central portion 11, which fits and turns within the slot 6, and has an arm 12, which is free to swing in the open side of the casing and is formed at its free end with an outwardly-projecting lug or enlargement 13, which normally extends beyond the casing to provide an operating portion which may be pressed upon by the hand or foot of the operator to force the arm 12 inward, and thereby swing the pawl 10 out of engagement with the ratchet-wheel. Bolts 14 pass through the rear portion of the cover-plate 8^a and block 4 and also through the supporting portion 1 and connect the casing to the latter, and another bolt 14' passes through the bifurcated end of the arm 5 and forms a pivot on which the intermediate portion 11 is fitted to pivot the pawl to swing. A coiled spring 15 is disposed within the casing and has one end suitably secured to the inner face of the block 4 and its outer end connected to the free end of the arm 12 of the pawl. This spring by expansion forces the arm 12 outward, thus projecting and maintaining the pawl 10 in engagement with the teeth of the ratchet-wheel 3, while permitting said pawl to vibrate and run over the curved surfaces of said teeth when the brake-rod is being turned to apply the brakes. When the motion of

- the brake-rod is arrested, however, retrograde movement of the ratchet-wheel is prevented by the engagement of the pawl with the straight shoulder of the coacting ratchet-tooth, with which it is securely held in engagement by the action of the spring 15, whose pressure is sufficient to prevent the pawl from moving out of engagement with said tooth unless pressure is applied directly to the projecting portion 13 of the pawl-arm 12. It will thus be seen that the pawl cannot be caused to jump out of engagement by any ordinary shock or strain, and thus will securely hold the rod or shaft 2 against rotation.
- 15 As the cover-plate, with its flange 9, forms with the block a housing which is open only at its forward side for the projection of the portion 13, the pawl is protected and prevented from becoming choked by ice or snow or other deleterious climatic influences and accordingly will always be in condition for operation.
- From the foregoing description, taken in connection with the accompanying drawings, 25 the construction and mode of operation of the pawl will be readily understood, and it will be seen that a construction is provided which is exceedingly simple and compact and which insures perfect engagement of the pawl with the ratchet-wheel at all times. The pawl may be readily substituted for the ordinary pawl and used in connection with existing brake mechanism without any changes in the construction thereof.
- 30 Changes in the form, proportions, and minor details of construction may be made within the scope of the invention without departing from the spirit or sacrificing any of the advantages thereof.
- 35 Having thus fully described the invention, what is claimed as new is—
1. In a brake mechanism, the combination with a brake-shaft provided with a ratchet-gear, of a casing having an open side arranged obliquely to the gear, a pawl pivoted between its ends at a corner portion of the casing and provided with oppositely-disposed arms, one of said arms having an engaging

end to coöperate with the ratchet-gear and the other a laterally-projecting finger-piece, 50 the arms of the pawl being disposed in substantial alinement so that the finger-piece will project through the obliquely-arranged open side of the casing when the pawl is in engagement with the ratchet-wheel.

55

2. A pawl comprising a block having a right-angled arm formed with a bifurcated extremity, said arm being formed with a shoulder, a cover-plate resting on the block and engaging said shoulder, a pawl pivoted in said bifurcated portion and provided with an engaging arm and a retracting arm, the latter extending into the casing, and a pressure-spring interposed between the block and retracting arm and acting on said arm to project the engaging arm, substantially as described.

60

3. In a brake mechanism, the combination with a brake-shaft carrying a ratchet-wheel, of a pivoted pawl having arms arranged substantially in longitudinal alinement, one of 70 said arms having an acting end to engage the ratchet-wheel, the other arm being provided with a laterally-projecting finger-piece, and a casing inclosing the latter-named arm of the pawl and having an open side disposed 75 obliquely to the direction of extension of the pawl to normally expose the finger-piece.

70

4. In a brake mechanism, the combination with a brake-shaft carrying a ratchet-wheel, of a block having arms disposed at right angles to each other, a cover-plate coacting with said arms to form a casing, a pawl pivoted to one of the arms and provided with an engaging arm and a retracting arm, the latter being formed with a finger-piece normally projecting from the casing, and a spring interposed between the other arm of the block and the retracting arm of the pawl and acting on said arm to project the engaging arm.

80

In testimony whereof I affix my signature in 85 presence of two witnesses.

ALEXANDER X. KENNEDY.
